UNITED STATES PATENT OFFICE.

ALEXANDRE BIGOT, OF PARIS, FRANCE.

DRYING KILN.

Application filed October 6, 1920. Serial No. 415,207.

To all whom it may concern:

Be it known that I, ALEXANDRE BIGOT, a citizen of the Republic of France, residing at Paris, Seine, in the Republic of France, have invented certain new and useful Improvements in Drying Kilns; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention has for its object to construct a continuous heating apparatus, the external walls of which lose by radiation only an insignificant number of calories and the inner walls of which are kept hot at a constant temperature, at determined points, by means of heat accumulators placed between the two walls. The inner hot walls surround chambers in which are placed, on suitable supports, the substances such as clay, gypsum, etc., it is desired to subject to heat. Owing to the nature of the substances which partially constitute them, these apparatus can only be employed at temperatures which are below a dull red heat; the same arrangement of walls and accumulators may serve for the construction of cooling chambers.

The external walls are made of or covered with incombustible materials, which are bad conductors of heat, such as light magnesia, the light infusible silicas, etc., in powder or agglomerated, the specific heat and conductivity of which are very low. The absorption and loss of heat by these walls will be very small.

The inner walls are constructed of rigid materials which are sufficiently conducting, such as plates of metals or of alloys, partitions and ceilings (floors) of thin armoured concrete, etc., with as large a surface as possible, in order to favour transmission and radiation towards the interior of the chambers.

The space comprised between these double walls is large or small, according to circumstances, it is filled with inert materials, such as bricks, pieces of cast iron, etc., forming regenerators and so arranged as to leave

passages between each of them. By natural or artificial aspiration or by compression, 55 hot gases are caused to circulate through the inert materials and between the walls. These gases give up the major portion of their heat to the inner wall and to the inert materials which become true accumulators of heat and regulate the emission of the heat towards the chambers. It is therefore advantageous to employ a considerable quantity of inert materials having as great a specific heat as possible. 60 65

A similar phenomenon will be produced if cold gases be sent into the accumulators: the inner walls will emit units of cold into the chambers.

Under the action of the hot gases and 70 of the heat transmitted into the chambers, the temperature of these chambers rises, and the materials which they contain are enabled to undergo a certain number of physical operations, such as: 75

Drying, in the case of moist clays, etc.

Dehydration, in the case of gypsum, etc.

Chemical decomposition, in the case of bicarbonate of soda, etc.

Combination, in the case of silico-limestone, and 80

The partial loss of water and chemical action as in the baking of bread.

Openings suitably made in the walls permit of the escape of the gases or vapours, 85 which are produced in the course of the heating, these gases or vapours may be collected if necessary in suitable apparatus.

Other openings may be made for the purpose of introducing into the chambers air 90 or gases which are heated or at the surrounding temperature in order to facilitate evaporation, or for raising the temperature, or for producing physical or chemical reactions. 95

The apparatus which forms the subject matter of the present invention may be constructed in different forms, and the applicant indicates below certain of them without this enunciation being limitative: 100

Stoves or driers on fixed supports or revolving platforms, etc.

Shaft furnaces with one or more chambers, etc.

Whatever be the form of these apparatus, 105 they can be heated by means of any kind

of grate whatever or by utilizing heat lost by the grates, furnaces, etc.

Of the various types which can be constructed, according to this invention, the applicant will proceed to describe, by way of example, and with reference to the accompanying drawings:

Figure 1 is a vertical section of a shaft furnace embodying another form of the invention;

Fig. 2 is a horizontal section on the line 7—7 of Fig. 1, and

Fig. 3 is a vertical section of a modified form of the shaft furnace.

15 This furnace may be of circular or polygonal form (see Figs. 1 and 2) is specially devised for the calcining of gypsum and is constructed in the following manner:

An inner vertical chamber C, C¹, C², has its 20 walls V of reinforced concrete, as thin as possible and covered internally with a coating of cement which withstands wear caused by the introduction into this lining of abrasive substances. This inner chamber is pierced 25 with openings d, d¹ the function of which will be hereinafter described. The part C¹ serves for the charging in of the crude gypsum. The part C² is provided at the end with two grinding cylinders e which act as 30 conveyors rotating in the direction of the arrows and the distance between the axles of which is adjustable at will.

At the outside of the furnace are arranged 35 pillars of reinforced concrete f resting at their base on a foundation of reinforced concrete and connected to each other by external beams or horizontal ties b.

The walls of the inner chamber are connected together by ceiling h, h¹, h² of reinforced concrete to the whole of the construction 40 of reinforced concrete which forms a monolith. Walls M of insulating materials form the outer walls of the furnace. These walls are covered outwardly with a coating 45 of cement or armoured cement i. Furthermore, insulating materials M¹, M², cover the ceiling h¹, h² and the upper part C¹ of the walls V.

The hot gases enter by the passage A into 50 a chamber E. This chamber communicates with the interior of the chamber C through a suitable number of openings d. The arches k of this chamber are pierced with numerous openings, likewise the ceiling h.

55 The spaces included between the walls V, M the brick arches k and the ceilings h, h¹ constitute galleries which are filled with inert materials forming accumulators. These galleries communicate with the chambers E 60 by openings in the arches k, with the chamber C through the openings d, and with the outside through the opening L made in the upper ceiling h¹ and which can be regulated at will by means of a damper.

65 An upper platform Q placed at the level

of the charging opening t surmounted by a hopper R supports one of the ends of the elevator which is not represented in Figure 1.

The furnace works in the following manner: The pieces of gypsum are placed in 70 the part C² up to the first openings d, by means of the charging doors z (see Figures 1 and 3), made in the outer wall of the furnace and in the wall V. After having closed these doors, the hot gases are admitted by 75 the passage A and the furnace is filled little by little by means of the elevator which delivers the gypsum in pieces through the opening t in the chamber C.

The hot gases enter for the greater part 80 into the accumulators G and a portion passing through the openings d and through the material where they give up the greatest portion of their heat and their temperature is lowered. The gases contained in the accumulators are drawn through the opening L by means of a fan l which causes them to enter through the openings d¹ in the chamber C¹, where they conclude by giving up their heat to the column of gypsum contained in 90 the said part C¹.

The upward movement of the gases in C¹ produces in the chamber C a suction which determines the entrance of the hot gases into this chamber through the openings d. The 95 mass of gypsum therein is subjected to heating both by radiation and conductivity, and to direct heating by a fraction of the hot gases.

The movement of the cylinders e regulates 100 the discharge of the plaster which falls crushed into trucks W, or on to a conveyor belt.

The suction produced towards the top of the chamber C causes a certain quantity of 105 air at the surrounding temperature to enter between the cylinders e. This air traverses the material in the chamber C²; it heats up gradually by cooling the material and proceeds to mix with the gases in the chamber C.

Figure 3 shows a modification of the shaft furnace above described. The hot gases enter through the passage A¹ above the stacks G. The suction of the gases is 115 effected through the pipe g¹ by means of a fan which is not shown in the figure.

The hot gases pass partially through the stacks and partially through the material by means of openings d which are made in 120 the walls of the central chamber C. An elevator x delivers the materials to be treated into a hopper R, on to a trap n which closes the chamber C at its upper part. It can rock on a shaft a by an automatic mechanism set in action from time to time by a special operating device on the elevator. This well-known device is not shown in Figure 3.

The shaft furnace may, it must be under- 125

stood be provided with apparatus for controlling pressure, temperature, etc.

What I claim and desire to secure by Letters Patent of the United States is:—

- 5 1. In apparatus for heating, a central heating chamber having highly conducting walls, outer walls spaced therefrom of insulating material, heat accumulating material included between said walls co-extensive with said chamber, means to supply hot gases to said heat-accumulating material, and means to vent a portion of said gases from said accumulating material to said chamber at different points along its 15 length.
- 10 2. In apparatus for heating, a vertical, central heating chamber, heat accumulators surrounding said chamber, means to supply hot gases to said accumulators, means to vent a portion of said gases from the accumulators to said chamber at different points along its 20 length, means to continu-

ously discharge said chamber at one end and means to continuously charge said chamber at the other end.

25 3. In apparatus for heating, a vertical, central heating chamber having highly conducting walls, heat accumulators surrounding said chamber throughout its length, a charging means for said chamber, means for continuously discharging said chamber, means to supply hot gas to said accumulators, means to vent gas from the accumulators to said chamber at different points along its length and means to discharge gas 30 from the end of the accumulators to said charging means and there mix with gases emanating from said chamber.

In testimony whereof I have signed this specification in the presence of a subscribing witness.

ALEXANDRE BIGOT.

Witness:

CLEMENT S. EDWARDS.
